DESIGN FOR A DOILY

Robert J. Hutt and George A. Hutt, Brooklyn,
N. Y.

Application October 20, 1934, Serial No. 53,704

Term of patent 3½ years

To all whom it may concern:

Be it known that we, Robert J. Hutt and George A. Hutt, have invented a new, original, and ornamental Design for Doilies, of which the following is a specification, reference being had to the accompanying drawing, forming part thereof.

The figure is a plan view of a doily showing our new design, and showing one-quarter of the design of the outer field in full line detail to set out novel circular and diagonally disposed fret figures connected by horizontal and vertical bars and a border of approximately uniform scallops; one corner figure of the inner field being shown in full line detail with a chain of links connecting the outer corner figures of the inner field which are indicated in dotted lines.

The outer field is continued in dotted lines from the full lined quarter section to complete the design.

We claim:

The ornamental design for a doily as shown and described.

GEORGE A. HUTT.
